L. H. MILLER, OF BALTIMORE, MARYLAND.

Letters Patent No. 73,742, dated January 28, 1868.

IMPROVEMENT IN PERMUTATION-LOCKS.

The Schedule referred to in these Letters Patent and making part of the same.

TO ALL WHOM IT MAY CONCERN:

Be it known that I, L. H. MILLER, of Baltimore, in the county of Baltimore, and State of Maryland, have invented a new and useful Improvement in Combination-Locks; and I do hereby declare the following to be a full, clear, and exact description of the same, reference being had to the accompanying drawings, which are made a part of this specification.

Figure 1 represents a horizontal section of the entire lock, operating-knob, and gearing at *v v*, fig. 2.

Figure 2, a vertical section of the same at *x x*, fig. 1.

Figure 3, a vertical section of the lock proper, at *y y*; fig. 1.

Figure 4 is a front view of the lock proper, with the face-plate removed, as indicated by the line *z z*, fig. 1.

Figure 5 is a rear view of one of the rotary tumblers or slotted wheels, hereinafter described.

Figure 6 represents a section of the same in the plane of its axis.

The red arrows in fig. 1 indicate the directions of the views, represented by the respective figures 2, 3, and 4.

In all the figures similar letters of reference indicate corresponding parts.

My improvements consist, first, in so constructing a permutation-lock and its accessories, as to bring the spindle or arbor which operates it on the outside of the lock proper, so as to avoid all danger of injury to the latter by violence applied to the external knob or spindle; second, in the combination of a pair of notched wheels mounted on the spindle, and deriving a common rotation therefrom, but so connected as to be capable of a limited independent rotation, so that, while they are rotated continuously in either direction, the hinged arm of the lock-bolt will ride on their peripheries, but, by turning them to a certain point and then reversing, their notches may be brought into coincident position with each other and with the hinged arm, so that the latter will engage in the notches and cause the rotation of the spindle to throw the bolt; third, in a peculiar construction of revolving tumblers.

In the drawings, A A' may represent portions of the frame of a safe-door, and B B the lock-case. C is a spindle, journalled in the front part, A, of the door-frame, externally, of the lock-case B, and carrying at its inner end a cog-wheel, D, which, projecting through a slot, *b*, in the lock-case, gears with a cog-wheel, E, mounted loosely upon a stationary stud-shaft, *e*, within the case B, and employed to communicate motion to the interior mechanism of the lock, in manner hereinafter explained.

C' represents the knob, by means of which the spindle C is rotated. *c* represents a dial, attached to and rotating with the spindle C, and *a* an index-point, on a stationary plate attached to the door.

Attached to and revolving with the cog-wheel E is a wheel, F, whose periphery is smooth and unbroken, save by a notch, *f*, (figs. 3 and 4.) G is a wheel, corresponding in size with the wheel F, and formed with a similar notch at *g*. The wheel G is mounted loosely on the stud-shaft *e*, and receives rotation from the wheel F by means of a pin, *f'*, projecting from the face of the said wheel F into a concentric slot, *g'*, in the wheel G. This device permits the wheel F to be rotated a short distance without moving the wheel G, but as soon as the pin *f'* reaches either end of the slot *g'*, the continued rotation of the wheel F will carry the wheel with it. The relative arrangement of the pin, slot, and notches in the wheels F G is such that, when the pin is at or near the mid-length of the slot, the two notches *f* and *g* will coincide, but while the pin is at either end of the slot the notches are not opposite each other, so that while the wheels are rotated continuously in either direction, they present an unbroken periphery.

The lock-bolt H is slotted near its rear end, so as to fit and slide over the flattened end of the stud *e*. I is an arm, pivoted at *i* to the lock-bolt, and formed with a laterally-projecting lug, *i'*, which is pressed against the periphery of the wheels F G by the action of a spring, J.

From the above description it will appear that while the wheels F G are rotated continuously in either direction, the lug *i'* will ride on their periphery, but if the rotation of said wheels be stopped, when the notch *g* of the wheel G reaches the position of the lug *i'*, and the rotation of the wheel F be reversed, the wheel G will rest until the notch *f* of the wheel F reaches the position of the lug *i'*, when the latter will be pressed into the said notches by the spring *J*, so that a further rotation of the wheel F, in the direction indicated by arrow 1 in fig. 3, will retract the bolt H. The reverse motion, (indicated by arrow 2,) after projecting the bolt, will throw the

lug i' out of the notches f and g , which it cannot re-enter until the said notches have again been brought into coincidence with each other and with the lug i' , in the manner already explained. Under these conditions there is no operative connection between the door-knob and the lock-bolt, and no possibility of locating the notches f g by feeling, and the forcible retraction of the bolt is prevented by the arm I engaging with a shoulder, b' , on the lock-case.

K is a plate, which is carried by the lock-bolt, and is capable of limited sliding motion thereon. Rigidly attached to the plate K is a horizontal stump, L , which projects through a slot in the lock-bolt, a little longer than the width of the stump, and through a slot in the lock-case, of a length equal to the extent of the motion of the bolt.

$M M^1 M^2 M^3 M^4$ represent a set of rotary tumblers, mounted on a stationary stud-shaft, N , and provided with radial slots m^5 , to permit the passage of the stump L when properly adjusted. The tumbler M is rotated by a cog-wheel, O , secured to its face, and gearing with the cog-wheel E , and has on its back a lug, m , to communicate rotation to the next tumbler M^1 . Each of the tumblers $M^1 M^2 M^3 M^4$ is constructed as represented in figs. 5 and 6, with an annular cavity, m^1 , a flaring hub, m^2 , for prehension, equidistant notches m^3 , around its periphery, and holes m^4 , extending from the bottoms of said notches through to the cavity m^1 . Each of the said tumblers carries a pin, Q , whose shank is inserted in either of the holes m^4 , and being split, as shown in fig. 5, is secure against accidental escape. The heads q of these pins occupy the notches m^3 , and project laterally, to a sufficient distance to communicate motion from one wheel to the other, and (in the case of the tumbler M^4) to receive motion from the lug m of the tumbler M . The notches m^3 are marked with successive letters and figures, as shown in fig. 5, corresponding letters and figures being marked upon the external rotary dial c .

P represents a cap-plate, pivoted at p to the back of the lock-case, and secured at its opposite edge by a thumb-screw, p' . By taking out the thumb-screw p' , and turning the cap-plate round upon its pivot, the tumbler-chamber is opened, permitting the removal of the tumblers, one by one, to change the combination on which the lock is set, by placing the pins Q q in suitable notches of the respective tumblers, the rear tumbler M^4 carrying the first letter or figure of the combination, the next, M^3 , the second, and so on.

R is a dog, pivoted at r to the lock-bolt, and confined at its other end by a screw, S , which passes through a slot, s , in the dog, so as to allow the latter a limited play on its pivot r . T is a pin, projecting from the slide K through an aperture in the dog R .

By this arrangement the dog offers no resistance to the retraction of the bolt, if the slide be carried along with it, but if, by reason of the obstruction of the sliding stump L , by either of the rotary tumblers $M M^1$, &c., the motion of the sliding plate K be arrested, the attempted retraction of the bolt will throw up the projecting arm r' of the dog, causing it to engage with the square end of the stud e , which thus performs the office of a stationary stump. This device effectually prevents the adjustment of the rotary tumblers by tentation or feeling.

On changing the combination it is always necessary to have five or more notches between the successive characters of the combination. If the lock be set on the combination $G O L D$, the mode of operation in order to unlock it is as follows: First, make one or more turns to the left, and stop on G ; second, reverse, and turn to the right, and pass the second letter of the combination, O , three times, and stop on it the fourth time; third, reverse, and turn to the left, and pass the third letter, L , twice, and stop on it the third time; fourth, reverse, and turn to the right, and pass the fourth letter, D , once, and stop on it the second time; fifth, reverse, and turn to the left, and stop on *; then turn to the right, and it will retract the bolt.

Having thus described my invention, what I claim as new, and desire to secure by Letters Patent, is—

1. A permutation-lock, so constructed as to bring the spindle or arbor which operates it on the outside of the lock proper, substantially as set forth.
2. The two wheels $F G$, capable of limited independent motion, in combination with a suitable catch, adapted to engage with the said wheels $F G$, when they are properly adjusted, and at other times riding on the unbroken periphery of the two wheels, substantially as explained.
3. The flaring or under-cut rim m^2 of the rotary tumblers, to adapt them for ready removal by hand, substantially as explained.
4. The combination of the notches m^3 , radial holes m^4 , and pin Q q , when constructed, arranged, and employed substantially as and for the purposes specified.

L. H. MILLER.
